UNITED STATES PATENT OFFICE.

MICHEL BURNIER, OF LAUSANNE, SWITZERLAND.

MASSAGING INSTRUMENT.

Application filed November 25, 1927, Serial No. 235,636, and in Switzerland March 31, 1927.

Constipation is usually caused by a spasm of the anal sphincter and by the inertness of the gut which lacks all capability of peristaltic movements. It has been found however, that 5 these derangements can be overcome by a massaging of the respective muscles if this massaging is accompanied by a massaging of the adjacent parts of the rectum. By mechanically acting on the anal sphincter, that is, by 10 letting it expand slowly and contract again, it is possible to restore its original suppleness and to cause an immediate discharging of the contents of the gut in the case where the faeces have collected at the end of the gut. The massaging of this part acts like a stimulant on the 15 peristaltic movement and causes the advancing of the contents of the gut up to the spot where it can be removed by a massaging of the sphincter.

20 The present invention relates to a massaging instrument which allows the said treatment to be performed either by the patient himself or by some other person. This instrument possesses at least two hollow jaws which 25 jointly form a cylinder and which are combined with a device for separating them. The jaws are provided at their front ends with bosses or heads having larger parts which connect them with the separating device.

30 The drawing represents four working examples:

Fig. 1 is an elevation and
Fig. 2 a plan view of one form;
Fig. 3 is a side elevation of the jaws shown
35 in Fig. 1,
Fig. 4 is a vertical section of Fig. 3,
Fig. 5 is a view half in plan and half in section;
Figs. 6 and 7 are fragmental views of a sec-
40 ond working form,

Fig. 6 representing in a side view of the closed jaws which enclose a device adapted to prevent the pinching of the mucous membranes and provided with an invaginated part 45 containing a lubricant, and

Fig. 7 showing the same structure as Fig. 6 but in working position, the left hand side in elevation and the right hand side in cross-section;

50 Fig. 8 is a perspective view of a third working form shown in Fig. 9 in side elevation and in Fig. 10 in end elevation.

Fig. 11 is a perspective view showing two different positions of a fourth working form 55 where the jaws are arranged obliquely with regard to the separating device—that is, ob-

liquely to the axis of the swinging separating arms as shown diagrammatically in Fig. 1.

The massaging instrument according to the form shown in Figs. 1 to 5 possesses two jaws 60 1 whereof each is secured to an arm 2 the two arms being hinged together at 7 and serving as separating means. Bosses 3 are formed at the front ends of these jaws like the bosses or heads of medicated plugs, the diameter of 65 these heads being larger than that of the parts connecting the same with the separating device. The rear part of the jaws is made of a rigid metal, or of a body like artificial eb- 70 onite, or of a flexible body like rubber, and carries an annular flange 4 preventing the jaws from entering too deeply. In order to prevent the mucous membranes from getting pinched by the closing jaws these jaws are provided with chamfered edges at 5 as may 75 be seen in Figs. 3 and 4.

Each jaw is secured to one end of the arms 2 of the separating device and its axis is ar- 80 ranged perpendicularly to the swinging plane of the arms, and, therefore, is parallel to the axis of the pivot 7. The rear parts 6 of the arms 2 are formed like handles. The pivot 7 85 may be for instance a pin or other member which can easily be removed and cleaned.

By moving the handles towards each other 85 as indicated by arrows 8 the jaws will separate according to the arrows 9 and the arms will assume the position shown in dotted lines in Fig. 2. The treatment by the instrument may be effected by the patient himself. After hav- 90 ing introduced the jaws into the anus they are gradually separated by compressing the handles 6. This movement is repeated several times and a massaging of the sphincter is thus obtained, which softens and puts a stop to the 95 anomalous spasm of the said muscle. Besides, the head 3 at the end of the jaws makes contact with the parts immediately behind the anus; and this repeated contact, the effect of 100 which may be increased by swinging the in- strument around a longitudinal axis, acts like a massaging of this part of the intestine which is the seat of the peristaltic movement. This massaging will cause the sliding down of the 105 contents of the gut if these had accumulated at the upper part of the gut.

The massaging instrument may comprise more than two jaws connected with a device for moving the same parallelly to themselves. The jaws may also have different diameters 110 according to the size and age of the patients.

The position of the jaws with regard to

the separating members may also be different from that shown in Fig. 1 with full lines. The longitudinal axis of the jaws may be arranged at an angle with the axis of the 5 pivot or hinge pin 7. In Fig. 1 three different positions at 30, 45 and 90° are indicated in dotted lines designated 10, 11 and 12. The convergent position of the two axes mentioned presents certain advantages. The 10 jaws will be opened in such a way that when massaging therewith the heads will be more distant from each other than the feet of the jaws. Thus a much stronger pressure will be put on to the rectum than on the sphincter 15 and this is sometimes very efficacious. Besides, with very fat persons the introducing of instruments with jaws having an inclined position is facilitated.

In the form shown in Figs. 6 and 7 the 20 instrument is provided, apart from the chamfered edges 5, with a device which prevents a pinching of the mucous membranes and which possesses an invagination containing a lubricant.

25 The space between the two hollow jaws (Fig. 6) is filled with an air bulb 13 made for instance of rubber and communicates by means of a canal or duct 14 with a second bulb 15 which is held between the front parts 30 of the separating members 2 (Fig. 2). An invagination 17 is formed in the head of the bulb 13 and may contain a lubricant 18 such as oil or a medicated plug.

When the massaging instrument has been 35 introduced the handles are compressed, whereby the bulb 15 will be contracted. The air in this bulb will be compressed and the bulb 13 will be inflated out and fill up the space between the opened jaws and thus the 40 pinching of the mucous membranes will be prevented. At the same time the compressed air will press against the invagination 17 and cause the discharge of the lubricant.

The second bulb 15 could also be arranged 45 otherwise than between the arms of the instrument and could be placed and worked independently from the instrument.

The spreading jaws could also have another form. They could for instance be arranged resiliently by means of springs and 50 similar to the devices employed for manual

gymnastics and could be kept closed by means of a catch while introducing them into the anus so that when the catch is released the jaws would be separated by the springs and 55 become efficacious.

The instrument can also be employed for the prophylaxis of the hemorrhoids and all such anal complaints, which can be favourably influenced by a massaging of the 60 intestine muscles.

The form according to Figs. 8, 9 and 10 differs from the instrument described in Figs. 1 to 5 only in the shape of the separating members. These are here flat massive arms 2 65 formed like handles. There are also two jaws having chamferings 5. The two jaws however touch each other only at the upper and lower ends so as to reduce to a minimum the possibility of pinching the mucous membranes. The pinching could be made quite impossible by means of a rubber hood put over 70 the two jaws.

Fig. 11 shows an instrument where the longitudinal axis of the jaws is arranged 75 with regard to the axis of the hinge or pivot in a similar way to that shown in Fig. 1. It is easily seen that the greater the inclination between the two axes the greater is the difference in the distances between the upper 80 and lower ends of the two jaws. This difference will be a maximum if the two axes are arranged perpendicularly to each other.

What I claim is:

A massaging instrument, comprising a 85 pair of companion semi-cylindrical jaws having their outer ends provided with mating bosses and their longitudinal edges chamfered, thereby to form conjointly, when closed, a hollow cylindrical member having 90 a head of enlarged diameter produced by the mating bosses; and a pair of operating levers pivoted directly together intermediate their ends for repeatedly moving the jaws laterally and bodily away from and toward each other in a plane which is disposed at an obtuse angle to the plane of pivotal movement of said levers, said jaws being mounted on the free front ends of the levers. 95

In testimony whereof I affix my signature.

DR. MICHEL BURNIER.
